CLAIM

The ornamental design for a detachable seat, as shown and described.

DESCRIPTION

FIG. 1 is a front perspective view showing our new design; FIG. 2 is a top view of FIG. 1; FIG. 3 is an end view of FIG. 1; FIG. 4 is a side view of FIG. 1; and, FIG. 5 is a bottom view of FIG. 1.

The broken lines are included for the purpose of illustrating environmental structure and form no part of the claimed designs used in FIG. 1.
